UNITED STATES PATENT OFFICE.

WILLIAM C. CAMPBELL, OF VASHON, WASHINGTON.

DRAFT-EQUALIZER.

SPECIFICATION forming part of Letters Patent No. 670,839, dated March 26, 1901.

Application filed June 30, 1900. Serial No. 22,159. (No model.)

To all whom it may concern:

Be it known that I, WILLIAM C. CAMPBELL, a citizen of the United States, residing at Vashon, in the county of King and State of Washington, have invented a certain new and useful Draft-Equalizer, of which the following is a specification.

My invention relates to draft-eveners, and has for its object to produce a device of this kind which can be manufactured cheaply and which will possess great strength and can be applied to all purposes for which draft-animals are used and which will prevent sudden strains or surges upon the animal and thereby give an even and steady pull.

With this object in view my invention consists in the improved construction and novel arrangement of parts of an evener, as will be hereinafter more particularly set forth.

In the accompanying drawings, in which the same reference-numerals indicate corresponding parts in each of the views in which they occur, Figure 1 is a perspective view of my improved evener. Fig. 2 is a front view of the doubletree portion. Fig. 3 is an end view of the doubletree portion. Fig. 4 is a front view of one of the singletrees. Fig. 5 is an end view of one of the singletrees. Fig. 6 is a transverse view of a modification.

Referring more particularly to the drawings, 1 indicates the doubletree portion of my improved draft-evener, and 2 2 indicate the singletrees, the said parts being of the usual length and arranged in the usual order relatively to each other. The forward edge of each of these pieces is preferably straight; but the rear edge is curved from the center nearly to each end, as shown at 3, the portion from the end of the curve to the end of the evener being substantially straight and parallel with the front edge, as shown at 4.

Rigidly secured to the rear portion of each end of the evener is a flat steel spring 5, which extends to a point substantially midway between the ends of the curve and the ends of the evener and is formed with an eye 6. The springs are secured in position by means of bolts 7 in the doubletree and by means of the fastening-clips 8 in the singletree. If desired, two more springs may be employed, the one adjacent to the evener be-

ing shorter than the others and provided with the ears 9 to engage with the opposite side of the leaves of the spring and hold them in alinement therewith. The doubletree is 55 provided with a vertically-arranged recess-plate 10, by means of which it is secured to the object to be drawn, and it may also be provided near each end with the ordinary clips 11 for the reception of the ordinary 60 stay-chains.

Pivottally secured in each eye 6 is a substantially U-shaped clip 12, the sides of which pass, respectively, above and below the end of the evener, and the bottom, which is located in front of the forward edge of the evener, is provided with an open hook 13 for the reception of the traces or other draft appliances. When the evener is made from wood, the upper and lower surfaces of the 70 ends thereof are provided with plates 14, the outer end of each of which is bent upwardly to form a stop 15 to prevent the clip 12 from swinging off the end of the evener.

As above described, it is evident that my 75 improved evener will possess great strength, as the strength of the wood will be reinforced by that of the spring located to the rear thereof. It will also be noticed that by curving the rear edge of the evener from the center 80 toward the ends the rigidity of the spring will be increased as its ends are drawn forward, owing to the decrease in the portion of the spring which is unsupported or projects beyond the curve. If desired, the curvature 85 of the spring may be increased from the center toward either end, which will increase the efficiency and desirability of my improved evener, and by using a series of leaves in each spring and making the inner ones shorter 90 than the outer ones the inner surface of the spring is virtually caused to curve away from the curved surfaces of the evener, thereby increasing the efficiency of the device. By providing the eveners with open hooks they 95 can be separated, so that the singletree can be used separately from the doubletree, if desired. The principle employed in my improved evener can be utilized for the singletree used upon light vehicles, thereby rendering the same very desirable in different fields of usefulness.

Instead of constructing the evener from wood it can be made from a piece of sheet metal curved or doubled upon itself longitudinally, so as to be U-shaped in cross-section, 5 as shown at 16 in Fig. 6. In this construction the attaching-hook 17 may be passed through an opening 18 in the end of the evener, or the ends of the evener may be bent upward in the same manner as the plates at the ends of the wooden evener, and the clip passes upon the opposite sides thereto, as heretofore described. In the metallic evener a strip of wood may be fitted within the bent portion 10 at the ends, or it may extend from one end to the other.

Having thus fully described my invention,

what I claim as new, and desire to secure by Letters Patent, is—

In a draft-evener, the combination, with an evener, the rear edge of which is curved from its center nearly to each end thereof, of a flat spring secured at its center to the center of the curved portion of the evener, each end of which extends to a point intermediate the end of the curve and the end of the evener 20 and is provided with an eye, of a hook secured in said eye and extending forward of the front edge of the evener.

WILLIAM C. CAMPBELL.
